UNITED STATES PATENT OFFICE

ALVIN S. JOHNSON, OF CHICAGO, ILLINOIS, AND WESLEY J. BALKWILL, OF ROCHESTER, NEW YORK, ASSIGNORS TO RICHARDSON CORPORATION, OF ROCHESTER, NEW YORK, A CORPORATION OF NEW YORK

DESIGN FOR A BEVERAGE DISPENSER

Application filed April 30, 1931. Serial No. 39,667. Term of patent 7 years.

To all whom it may concern:

Be it known that we, ALVIN S. JOHNSON and WESLEY J. BALKWILL, both citizens of the United States of America, residing at Chicago, in the county of Cook and State of Illinois, and Rochester, in the county of Monroe and State of New York, respectively, have invented a new, original, and ornamental Design for a Beverage Dispenser, of which the following is a specification, reference being had to the accompanying drawing, forming a part thereof.

The figure of the drawing is a perspective view of a beverage dispenser with the central or body portion lined to represent hammered metal, the opposite or rear side of the dispenser having substantially the same appearance except that it has a dispensing conventional faucet projecting therefrom.

We claim:

The ornamental design for a beverage dispenser, as shown and described.

ALVIN S. JOHNSON.
WESLEY J. BALKWILL.
